(57)

CLAIM

The ornamental design for fabric electrode assembly, as shown and described.

DESCRIPTION

FIG. 1 is a top, plan view of a fabric electrode assembly showing our new ornamental design.

FIG. 2 is a bottom plan view thereof.

FIG. 3 is a front elevation view thereof.

FIG. 4 is a back elevation view thereof.

FIG. 5 is a right elevational view thereof; and,

FIG. 6 is a left elevational view thereof.

The broken lines depict portions of the fabric electrode assembly that form no part of the claimed design.

The drawings include symbolic break lines along the lengths of the curving portions of the design. Any portion of the fabric electrode assembly between the break lines forms no part of the claimed design.

1 Claim, 2 Drawing Sheets# US D866,199 S
